[57] **CLAIM**

The ornamental design for a packaging container for food or the like, as shown and described.

DESCRIPTION

FIG. 1 is a perspective view of a packaging container for food or the like showing my new design;

FIG. 2 is a front elevational view thereof;

FIG. 3 is a side elevational view thereof;

FIG. 4 is a top plan view thereof;

FIG. 5 is a bottom plan view thereof;

FIG. 6 is a rear elevational view thereof; and

FIG. 7 is a side elevational view partly broken away showing the container in a partially opened position.

*Fig.1.**Fig.4.**Fig.3.**Fig.2.**Fig.7.**Fig.5.**Fig.6.*
